(57) **CLAIM**

We claim the ornamental design for fluorescent tube light low bay reflector, as shown and described.

DESCRIPTION

FIG. 1 is a top plan view of the fluorescent tube light low bay reflector, showing our new design;

FIG. 2 is a cross sectional view thereof, taken along line 2—2 of FIG. 1;

FIG. 3 is a cross sectional view thereof, taken along line 3—3 of FIG. 1;

FIG. 4 is a cross sectional view thereof, taken along line 4—4 of FIG. 1;

FIG. 5 is a cross sectional view thereof, taken along line 5—5 of FIG. 1;

FIG. 6—is a left side elevation view, and the right side elevation view is a mirror image of the left side elevation view;

FIG. 7—is a perspective top view; and,

FIG. 8 is a bottom plan view of the fluorescent tube light low bay reflector.

[The broken lines shown in FIGS. 1, 2, 3, 4, 5, 7 and 8 are for illustration only, and form no part of this invention.] *The evenly spaced broken lines in FIGS. 1, 7 and 8 depict an unclaimed portion of the article. The unevenly spaced broken lines in FIGS. 2 through 5 depict an environmental structure that forms no part of the claimed design.*
